UNITED STATES PATENT OFFICE

2,233,910

EGG CLEANING MACHINE

Alfred Benjamin Carper, Creswell, Oreg.

Application January 10, 1940, Serial No. 313,263

9 Claims. (Cl. 51—73)

The invention relates to an improved egg-cleaning machine, the object of which is to provide a simple, relatively inexpensive machine for mechanically dry cleaning soiled and dirty eggs, 5 so as to render them more sanitary and attractive for market without injuring their keeping quality.

One form of the invention is illustrated in the accompanying drawing, in which Figure 1 is a 10 vertical section of the entire machine with the hood removed and the location of tapered spurs 18, 18, hereinafter referred to, indicated by dotted lines; Figure 2, a vertical front view of the machine with the hood shown in a closed position; and Figure 3, a detailed view in perspective of the rotating crossarm and its brackets, showing one tapered spur 18 quite clearly and indicating the location of the other identical tapered spur 18. Figure 3 is drawn approximately two-thirds the size I consider most practical in this 15 machine. Figures 1 and 2 are drawn to scale one-half the size of Figure 3.

The base 1, the block 2, and the hangers 3, 3, secured to the base 1, constitute the framework 20 of the machine. In the hangers 3, 3 turns the hollow drive shaft 4, carrying a drive pulley 5 and a flange 6 to which is attached a crossarm 7. Attached to crossarm 7 are fixed bracket 8 and pivoted bracket 9, between which is strung the abrasive band 10, referred to hereinafter.

Projecting into hollow drive shaft 4, but not in contact therewith, is the stationary hollow center rod 11 which is held by the stationary bracket 12, fastened to block 2 (see Figure 1). The 25 stationary bracket 12 provides for slight adjustment in all directions of the position of the aforesaid stationary hollow center rod 11, so as to assure its perfect alignment inside of the hollow drive shaft 4 and prevent contact therein. 30 Horizontal adjustment is provided, by having the stationary bracket 12 bolted to block 2 through elliptical holes; and by having the stationary hollow center rod 11 threaded, so as to screw into one end of the stationary bracket 12, 35 and provided with a locknut 13. Vertical adjustment is accomplished by inserting shims made of cardboard or sheet metal between the stationary bracket 12 and the block 2.

A pad 14, consisting of a piece of sponge rubber cemented to a metal disc, is attached to a 40 plunger rod 15 sliding inside the end of the stationary hollow center rod 11, but being prevented from rotating by a pin operating in a 45 slot as shown in Figure 1. A coil spring 16 is

placed around the plunger rod 15 and exerts pressure upon the pad 14.

The crossarm 7 previously referred to, and shown in perspective in Figure 3, is provided, at one end with the fixed bracket 8, attached solidly; 5 and at the other end, the pivoted bracket 9, pivoted on pin 17. Fastened, one in the fixed bracket 8 and one in the pivoted bracket 9, are tapered spurs 18, 18 between which is strung the abrasive band 10 with abrasive surfaces turned 10 in (see Figure 1). The abrasive band 10 is held taut by spring 19 operating in pivoted bracket 9. The abrasive band 10, strung between tapered spurs 18, 18 and rotated by hollow drive shaft 4, is the cleaning element in this machine. It 15 is made of emery cloth or any suitable flexible abrasive material and is easily replaced when the abrasive substance wears out.

When the machine is being operated, the egg 20 is cleaned one-half at a time by being shoved end first; between the abrasive surfaces of abrasive band 10 as said band is rotated around the egg by the hollow drive shaft 4; and against the pad 14 which does not rotate, but which 25 will move back with the egg as the egg is pressed forcibly against it. The egg is held firmly between the operator's fingers and the pad 14. The egg is furthermore steadied by contact with a padded stationary rest 20 which is shaped to 30 fit the egg as shown in Figures 1 and 2. The pad 14, operated by the coil spring 16, will eject the egg from the machine when the pressure of the operator's fingers is lessened. The tapered spurs 18, 18, previously referred to, are tapered in 35 such a manner as to hold the front edges of the abrasive surfaces of abrasive band 10 separated, so as to permit the egg to enter the machine easily; and the back edges of the said abrasive surfaces of abrasive band 10 close together, so as to clean the end of the egg as the egg is shoved 40 into the machine.

A hood 21 is used to cover the rotating crossarm 7 and its brackets 8 and 9. The hood 21 is hinged to the base 1 by the loose-pin hinge 22, 45 shown in Figure 2. Figure 1 shows the machine with the hood 21 removed and one-half of the loose-pin hinge 22 remaining attached to the base 1. The hood 21 closes down between stops 23 and 23 making a dust-tight closure. A friction catch or a hook and eye may be used to 50 fasten it down. To permit the hood 21 to open on loose-pin hinge 22, a curved slot is cut in the back of the hood 21 where it fits over the hollow drive shaft 4. This slot is not shown in the drawing. A sheet of metal 24 (see Figure 1) 55

is fastened to the base 1 in such a manner as to cover the aforesaid curved slot when the hood 21 is in a closed position. The hood 21, when it is closed, does not contact any of the moving parts of the machine.

5 A recess 25, indicated by dotted lines in Figures 1 and 2, is cut into base 1 directly beneath the hood 21. The recess 25 communicates by passageway 26 with opening 27. The dust created 10 by the egg-cleaning process, directed into recess 25 by hood 21, is forced out through passageway 26 to the opening 27 by the current of air created by the rotating crossarm 7 and its brackets 8 and 9. This opening 27 may be connected to a tube or pipe leading away from the machine, so as to carry the dust and dirt entirely away from the operator.

I claim:

1. In an egg-cleaning machine, in combination 20 with abrasive surfaces rotated perimetricaly about an egg, a non-rotative pad reciprocatively mounted on the axis of the aforesaid rotated abrasive surfaces and in line with the entry of the egg into the machine, resilient means for exerting pressure axially to the said pad, and means for limiting the reciprocatative movement of the said pad.

2. An egg-cleaning machine comprising a rotary tubular drive shaft, a crossarm attached to 30 one end of the said rotary tubular drive shaft, a single endless band of emery cloth or other similar flexible abrasive material turned with the abrasive surface in and strung between two brackets attached to opposite ends of the said crossarm and opposed abrasive inner surface regions of which single endless band are respectively brought into operative engagement with opposed surface regions of an egg and which said opposed abrasive inner surface regions of said 35 single endless band are rotated perimetricaly about the egg by the rotation of the aforesaid rotary tubular drive shaft and the aforesaid crossarm, resilient means for tensioning the aforesaid single endless band, a non-rotative pad reciprocatively mounted on the axis of the aforesaid 40 rotary tubular drive shaft and in line with the entry of the egg into the machine, resilient means for exerting pressure axially to the said pad, means for limiting the reciprocatative movement of the said pad, a padded stationary rest the padded surface of which is contacted by the egg as the egg enters the machine, and a removable stationary hood means serving to cover the operative parts of the machine, said hood having 50 an opening therethrough to allow the operative parts to be accessible.

3. The combination, in an egg-cleaning machine, of a rotary hollow drive shaft, a stationary hollow center rod projecting into or through 60 the said rotary hollow drive shaft, a plunger rod reciprocatively mounted inside the end of the said stationary hollow center rod and actuated by a spring, a pad attached to the end of the said plunger rod, means for limiting the reciprocative movement of the said plunger rod, and means for preventing the rotation of the said plunger rod.

4. An egg-cleaning machine comprising a rotatably mounted tubular shaft, means for rotating 70 the said tubular shaft, a crossarm attached to one end of the said tubular shaft, a fixed bracket and a pivoted companion bracket that are attached to opposite ends of the said crossarm, duplicate band support means carried by each 75 of the said brackets and adapted to have an end-

less band of flexible material strung between them, said duplicate band support means serving to support such a band in such a manner as to tend to hold the opposed inner surface regions of such a band at an angle to each other, 5 an endless band of flexible material having an inner abrasive surface and which endless band is strung between the said duplicate band support means in the manner stated above and opposed abrasive inner surface regions of which endless band are brought into operative engagement with opposed surface regions of an egg and which opposed abrasive inner surface regions of said endless band are rotated perimetricaly about the egg by the rotation of the aforesaid tubular shaft and 10 the aforesaid crossarm, resilient means carried by the aforesaid pivoted bracket for tensioning the said endless band, a pad reciprocatively mounted on the axis of the aforesaid tubular shaft and in line with the entry of the egg into 20 the machine, resilient means for exerting pressure axially to the said pad, means for limiting the reciprocative movement of the said pad, means for preventing the rotation of the said pad, means serving to contact and steady the egg as the egg enters the machine, a removable stationary hood means serving to cover the operative parts of the machine, said hood having an opening therethrough to allow the operative parts to be accessible, and a passageway communicating with the interior of the said hood.

5. The combination, in an egg-cleaning machine, of a rotary crossarm, a fixed bracket and a pivoted companion bracket that are attached to opposite ends of the said rotary crossarm, an endless band of flexible material having an inner abrasive surface and which endless band is strung between the said brackets and opposed abrasive inner surface regions of which endless band are respectively brought into operative engagement with opposed surface regions of an egg and which opposed abrasive inner surface regions of said endless band are rotated perimetricaly about the egg by the rotation of the aforesaid rotary crossarm, and resilient means 45 carried by the aforesaid pivoted bracket for tensioning the said endless band.

6. In an egg-cleaning machine, in combination with an endless band of flexible material having an inner abrasive surface, duplicate band support means mounted so as to allow the said endless band to be strung between them and the whole to be rotated about an axis which is perpendicular to the approximate center of the said endless band, said duplicate band support 50 means serving to support the said endless band in such a manner as to tend to hold the opposed abrasive inner surface regions of the said endless band at an angle to each other, means for rotating the same, and resilient means for tensioning the said endless band.

7. The combination, in an egg-cleaning machine, of a rotary crossarm, abrasive means carried by the said rotary crossarm and which abrasive means operatively engage an egg and 65 are rotated perimetricaly about the egg by the rotation of the said rotary crossarm, a removable stationary hood means serving to cover the said rotary crossarm, said hood having an opening therethrough to allow the operative parts 70 to be accessible, a passageway communicating with the interior of the said hood, and means carried by the aforesaid rotary crossarm serving to create an air current inside of the said hood thereby forcing the dust created inside 75

of the said hood by the operation of the machine out through the said passageway.

8. The combination, in an egg-cleaning machine, of a rotatably mounted hollow shaft, 5 means for rotating the same, a stationary member projecting into or through the said hollow shaft, adjustable external stationary means for supporting the said stationary member independently of the said hollow shaft, a plunger 10 rod reciprocatively mounted in the end of the aforesaid stationary member, a pad attached to the end of the said plunger rod, resilient means for exerting pressure axially to the said plunger

rod, means for limiting the reciprocative movement of the said plunger rod, and means for preventing the rotation of the said plunger rod.

9. The combination, in an egg-cleaning machine, of a rotatably mounted crossarm, means 5 for rotating the same, abrasive means carried by the said crossarm and which abrasive means operatively engage an egg and are rotated peripherally about the egg by the rotation of the said crossarm, and means serving to contact and 10 steady the egg as the egg enters the machine.
